UNITED STATES PATENT OFFICE.

LUTHER M. GUNNERSON, OF STANWOOD, WASHINGTON, ASSIGNOR OF ONE-HALF TO
NELS P. GUNNERSON, OF STANWOOD, WASHINGTON.

PENCIL ATTACHMENT.

1,169,029.

Specification of Letters Patent. Patented Jan. 18, 1916.

Application filed March 23, 1915. Serial No. 16,361.

To all whom it may concern:

Be it known that I, LUTHER M. GUNNERSON, a citizen of the United States, residing at Stanwood, in the county of Snohomish 5 and State of Washington, have invented certain new and useful Improvements in Pencil Attachments; and I do hereby declare the following to be a full, clear, and exact description of the invention, such as will

enable others skilled in the art to which it appertains to make and use the same.

This invention has for its object to provide a simple and efficient attachment for pencils, pens and the like for illuminating 15 the object written upon.

Another object is the provision of a simple illuminating attachment for pencils which may be inexpensively manufactured and applied to use upon practically any 20 type of pencil.

With these and other objects in view, the invention consists in the novel construction, arrangement and formation of parts as will be hereinafter specifically described, claimed 25 and illustrated in the accompanying drawing, in which:

Figure 1 represents a sectional view through the attachment, illustrating a fragment of a pencil. Fig. 2 represents a side 30 elevation of the attachment in use. Fig. 3 represents a bottom plan view of the attachment removed.

Referring to the drawing in detail, wherein similar reference numerals designate corresponding parts throughout the 35 several views, the numeral 5 indicates the tubular U-shaped body of the attachment which is preferably formed of hard rubber or other insulating material and is provided 40 in the pencil-receiving end 6 thereof with an annular shoulder 7 for engaging and limiting the inward movement of a pencil 8^a. The bore of the end 6 is preferably tapered inwardly from the edge to the shoulder 7 to 45 insure tight frictional engagement of the end of the pencil 8^a therein to prevent loss or disengagement of the attachment. The opposite end of the body 5 is formed with internal screwthreads to receive an electric 50 lamp 8, one of the contacts of which is engaged by a spring contact member 9 secured

in the web portion of the U-shaped body 5. The other or central contact or electrode of the lamp 8 is engaged by a relatively stationary contact 10 secured to the U-shaped 55 member adjacent the lamp-receiving end thereof. The contact 9 is preferably formed of spring metal and is of adequate width to snugly fit between the screwthreads of the lamp 8. 60

The contacts 9 and 10 are connected with wires 11 and 12, respectively, which are extended outwardly of the body 5 through an aperture 13 and are connected with a battery or other suitable source of electro-magnetic force 14. 65

From the foregoing it is clearly apparent that by the peculiar shape of the body member 5 and the arrangement of the lamp 8 with relation to the pencil 8^a, the rays of 70 light from the lamp are directed toward the pointed end of the pencil and thus sufficiently illuminate the object written upon.

What I claim is:

1. An attachment for pencils and the like 75 comprising a tubular U-shaped body having open ends, an internal shoulder formed adjacent one end adapted to limit the inward movement of a pencil relative thereto, illuminating means removably secured in 80 the opposite end of said body.

2. An attachment for pencils and the like comprising a tubular U-shaped body, an internal shoulder formed adjacent one end of 85 said body adapted to limit the inward movement of a lead pencil relative thereto, an electric lamp removably secured in the opposite end of said body, contacts secured in said body for engaging the electrodes of said lamp, and wires secured to said contacts and 90 extending exteriorly of said body.

3. An attachment for pencils and the like comprising a tubular U-shaped body having open ends, internal screwthreads at one end 95 of said body, the opposite end of said body being adapted to receive a lead pencil or the like, an electric lamp removably secured in the screwthreaded end of said body, and contacts secured in said body for engaging the electrodes of said lamp. 100

4. An attachment for pencils and the like comprising a tubular U-shaped body hav-

ing open ends, an internal shoulder formed adjacent one end of said body adapted to limit the inward movement of a lead pencil, internal screwthreads formed in the opposite end of said body, an electric lamp removably secured in the threaded end of said body, contacts secured in said body engaging the electrodes of said lamp, and wires

secured to said electrodes and extending exteriorly of said casing.

In testimony whereof I affix my signature in presence of two witnesses.

LUTHER M. GUNNERSON.
